UNITED STATES PATENT OFFICE.

HOMER H. WAMPLER, OF DAYTON, OHIO.

BOTTLE-CAPPING DEVICE.

1,413,640.

Specification of Letters Patent. Patented Apr. 25, 1922.

Application filed January 24, 1921. Serial No. 439,415.

To all whom it may concern:

Be it known that I, HOMER H. WAMPLER, a citizen of the United States, residing at Dayton, in the county of Montgomery and 5 State of Ohio, have invented certain new and useful Improvements in Bottle-Capping Devices, of which the following is a specification.

The principal object of my invention is to 10 provide a bottle-capping device which contains a rotatable member that carries a series of cap-applying heads for different sized bottles and jars. It is thus possible, with one machine, to cap bottles and jars of different sizes, by merely turning the capping member to a position to bring a selected head over the bottle or jar to be capped, and then exerting the necessary pressure upon it by my improved cam means.

20 My bottle-capping device is particularly adapted for use in connection with the cold-pack process of canning, wherein a bottle or jar is placed in hot water, with its cap thereon water-tight, but not air-tight. Temporary and permanent capping heads may 25 be carried by my rotatable member, whereby one head may be used to apply a cap on a bottle or jar in a temporary or water-tight manner, after which the member may be rotated to bring over the bottle or jar, when the canning operation is completed, a head that will make the water-tight cap, air-tight, or permanently seal it.

Other important and incidental objects 35 will be brought out in the following specification, and particularly set forth in the subjoined claims.

In the accompanying drawings, Figure 1 is a side elevational view of my improved 40 bottle-capping device. Figure 2 is a top plan view of the same. Figure 3 is a horizontal sectional view on the line 3—3 of Figure 1. Figure 4 is a vertical sectional view on the line 4—4 of Figure 2, showing 45 the rotatable bottle capping means. Figure 5 is a vertical sectional view on the line 5—5 of Figure 1. Figure 6 is a side elevational view of an annular capping member carrying heads for temporarily and permanently 50 capping bottles and jars in the cold-pack process of canning. And Figure 7 is a top plan view of one of the temporary capping heads.

Throughout the specification and drawings, similar reference characters denote corresponding parts.

Referring to the accompanying drawings, the numeral 1 designates a base upon the front portion of which a jar 2 is placed, and which terminates at its rear end in an upright tubular portion 3 which receives a rod or standard 4 that is firmly held in the latter by a set screw 5. The base 1 may be placed upon a table, stand or other supporting structure. (See Figure 1.)

Vertically movable along the rod 4 is an elongated slide 6 adapted to be firmly held in an adjusted position by set screws 7, 7. The slide 6 has a pair of outwardly projecting integral arms 8, 8 which are oppositely curved near their inner ends to form an elliptical opening or clearance between them for a purpose to be hereinafter described. (See Figure 2.)

Secured between the front ends of the arms 8, 8 of the slide, by means of a pin 9 and a pivot pin 10, is a guide block 11. The pin 10 forms a fulcrum for the cam extensions 12, 12 of a handle 13, which straddle the front ends of the arms 8, 8 of the slide 6. These cam extensions 12, 12 at their rear ends taper into oppositely bulged portions 14, 14 respectively, to provide a space or clearance between them for a purpose to be hereinafter described. (See Figures 1 and 2.)

Vertically movable over the guide block 11 between the front ends 8, 8 of the slide 6, is a circular member or cylinder 15 provided with a rectangular slot 16 through which the 90 guide block 11 loosely projects. This slot permits the cylinder 15 to have a free up and down movement over the guide block 11 for a purpose soon to be described. (See Figure 4.)

Rotatable around the cylinder 15 is an annular capping-head member 17 provided in the periphery of which are cap-applying heads 18 that are adapted to pass through the clearance spaces between the arms 8, 8 100 and cam extensions 12, 12, above described. These cap-applying heads 18 are of different sizes to cap different sized bottles and jars. Oppositely disposed screws 19, 19 are so inserted in the cylinder 15 that their heads 105 will project a sufficient distance beyond the perimeter of the latter to form flanges between which the reduced inner peripheral portion 20 of the capping member 17 moves, to hold the latter on the cylinder. (See Figure 3.)

The capping member 17 is free to be

turned around the cylinder 15, between the screws 19, 19, to bring a selected head 18 over the jar 2. The selected head is held in such a position by a pointed stop pin 21 that is pressed outwardly from a hole 22 in the cylinder, into a tapered recess 23 in the inner surface of the annular member 17. There are four of these recesses, corresponding in number to the four cap-applying heads 18, whereby, when a selected head 18 is in its proper position over the jar 2, the stop pin 21 will be projected into one of these recesses 23 by a spring 24 in the hole 22. (See Figures 3 and 4.)

15 When a selected head 18 is held in its proper position over the jar 2, said head may be depressed with sufficient force over the cap 25 of the jar 2 by the following means, to apply said cap firmly to the jar.

20 Referring to Figures 1 and 5, there is secured in the lower portion of the cylinder 15, a transverse spindle 26 whose ends project a sufficient distance beyond the sides of the cylinder to receive rolls 27, 27 upon which the cam extensions 12, 12 of the handle 13 are adapted to bear. Therefore, when the handle 13 is depressed, the cam extensions 12, 12 thereof will bear down upon the rolls 27, 27 to force the cylinder 15 and the

25 annular capping member 17 downwardly with sufficient force to cause the selected cap-applying head 18 on the latter to apply the cap 25 to the jar. The block 11, which projects through the slot 16 in the cylinder 15, guides the latter during its downward movement, and also during its upward movement when returned to its normal position by a spring 28 whose upper end rests in a hole in the cylinder and whose lower end rests in a hole in the block. (See Figures 4 and 5.)

In Figure 6 I have shown an annular capping member 17, provided in its periphery with heads 29 for temporarily applying caps 45 on bottles and jars during the cold-pack process of canning, and with heads 30 for permanently applying those caps on said bottles and jars after the canning operation is completed. The heads 29, which differ 50 only in size, have bosses 31 on their inner surfaces to engage the bottle or jar cap in such a manner that it will be made watertight thereon, and not air-tight. Thereafter, when the cold-pack operations are completed, the annular head 17 may be rotated to a position wherein a head 30, corresponding 55 in size to the head 29 which has been used, may be forced downwardly upon the cap to make it air-tight upon the said bottle or jar.

In operation, a bottle or jar is placed upon the front portion of the base 1 and the annular member 17 rotated about the cylinder 15 to a position to bring a selected head 18 over said bottle or jar. The recesses 23 are

shallow enough to permit the stop pin 21 to be pushed inwardly when a slight initial force is applied to the annular member 17 to start its rotation. When the selected head 18 is in its proper position over the top of the bottle or jar to be capped, the outer end of the pin 21 will enter one of the recesses 23 to hold it in such a position. The jar 2, which is the object to be capped in Figure 1, is then adjusted on the base so that it will have a position directly under the selected head 18. The slide 6 is then set at that point on the rod 4 which will bring the arrow 32 on the slide in approximately the same horizontal plane as the top of the jar. Pressure is then applied to the handle 13, whereupon the cam extensions 12, 12 thereon will force the cap-applying head 18 downwardly to apply the cap 25 firmly on the top of the jar. Thereafter, when pressure is released on the handle, the spring 28 will return the capping means to their normal position.

It is thus seen that my invention provides a selective capping mechanism by means of which bottles or jars of various sizes may be readily and efficiently capped with one machine.

Having described my invention, I claim:

1. In a bottle capping device, the combination with pressure means, of a temporary-capping head, a permanent-capping head, and a movable member on which said heads are mounted, to bring, first the temporary-capping head and then the permanent-capping head to a position to be actuated by said pressure means. 95
2. In a bottle capping device, the combination with a pressure member, of temporary-capping heads, permanent-capping heads, and a rotatable member on which said temporary and permanent capping heads are alternately mounted, to bring them successively to a position under the pressure member, for the purpose specified. 100
3. In a bottle capping device, the combination with pressure means, of a vertically-movable, non-rotatable cylinder adapted to be forced downwardly by said pressure means, an annular head rotatable around said cylinder, and a series of cap-applying heads of different sizes carried by said annular head, for the purpose specified. 110
4. In a bottle capping device, the combination with a standard, of a vertically adjustable slide thereon, a horizontal yoke extension on said slide, a guide block secured in said yoke extension, a cylinder having a vertical slot to receive said guide block, vertically movable through said yoke extension, an annular master head rotatable around said cylinder, a series of cap-applying heads carried by said master head, side projections on said cylinder, a pressure handle, and a pair of cam extensions on said handle, piv- 120
- 65
- 130

totally secured to said yoke extension, for engagement with the side projections on the cylinder, to force the latter, and said master head, downwardly when the handle is depressed, for the purpose specified.

5. In a bottle capping device, the combination with a standard, of a vertically adjustable slide thereon, a horizontal extension on said slide, a guide secured in said extension, a cylinder having a vertical opening 10 to receive said guide, vertically movable through said extension, an annular master

head rotatable around said cylinder, a series of cap-applying heads carried by said master head, and pressure means pivotally secured to said horizontal extension, for engagement with said cylinder, to force the latter and said master head downwardly, for the purpose specified.

In testimony whereof I have hereunto set 20 my hand this 20th day of January, 1921.

HOMER H. WAMPLER.

Witness:

HOWARD P. SMITH.
